(57) **CLAIM**

The ornamental design for a dual level low-profile light bar with optional speaker, as shown and described.

DESCRIPTION

FIG. 1 is a perspective view of a first embodiment of a light bar according to our new design without a speaker.

FIG. 2 is a front elevation view of the light bar of FIG. 1.

FIG. 3 is a right side elevation view of the light bar of FIG. 1.

FIG. 4 is a top plan view of the light bar of FIG. 1.

FIG. 5 is a rear elevation view of the light bar of FIG. 1.

FIG. 6 is a left side elevation view of the light bar of FIG. 1.

FIG. 7 is a bottom plan view of the light bar of FIG. 1.

FIG. 8 is a perspective view of a second embodiment of a light bar according to our new design with a speaker.

FIG. 9 is a front elevation view of the light bar of FIG. 8.

FIG. 10 is a right side elevation view of the light bar of FIG. 8.

FIG. 11 is a top plan view of the light bar of FIG. 8.

FIG. 12 is a rear elevation view of the light bar of FIG. 8.

FIG. 13 is a left side elevation view of the light bar of FIG. 8; and,

FIG. 14 is a bottom plan view of the light bar of FIG. 8.

The broken lines (where present) in FIGS. 1-14 illustrate portions of the dual level low-profile light bar with optional speaker that form no part of the claimed design.
